ABSTRACT OF THE DISCLOSURE

Emulsifying agents characterized by unusual mildness toward the skin are described which consist essentially of a synergistic combination of a water soluble taurine salt of the general formula:

wherein R_1 is selected from the group consisting of alkyl and oxaalkyl radicals having from 10 to 18 carbon atoms and M is a water-solubilizing cation and a surface active organic sulfate or sulfonate detergent, the organic portion of which consists of the atoms C, H, O or amido nitrogen and having from 8 to 20 carbon atoms. The taurine salt is preferably present in a weight ratio of approximately 1:3 to 3:1 with the sulfate or sulfonate detergent ingredient.

This application is a continuation-in-part of our co-pending application Ser. No. 573,192, filed Aug. 18, 1966 now abandoned.

This invention relates to a novel emulsifier, and more particularly, concerns compositions comprising a synergistic combination of hydroxyalkyl-N-methyltaurines with surface active organic sulfate and sulfonate detergents. These compositions have markedly improved characteristics which promote the formation and stabilization of oil and water emulsions which exhibit unusual mildness toward the skin.

It is well known in the art that surface active compounds in general act as emulsifying agents and are of primary importance in stabilizing oil-in-water or water-in-oil emulsification. The ability to form such emulsions is an important property for dishwashing purposes as well as for a variety of other applications.

The preparation and utility of hydroxyalkyl-N-methyltaurines as active detergent ingredients has been disclosed in the Cahn et al. Canadian Pat. No. 701,363. However, it has been heretofore unknown that these materials exhibit unusually strong synergistic effects when taken in combination with organic sulfates and sulfonates as emulsifiers for oil and water systems. The combined materials are many times more effective as an emulsifying system than either of the individual materials alone. These combinations are also unexpectedly mild detergents, and hence especially suitable for dishwashing purposes.

The salts of the taurines employed in the present invention have the following formula:

in which R_1 is an alkyl or oxaalkyl having from about 10 to about 18 carbon atoms, and M is a water-solubilizing cation. In preferred compounds, R_1 contains from 12 to 18 carbon atoms. The water-solubilizing cation used may be any of those well known in the art, such as the alkali metal ions, ammonium ions, or the substituted ammonium ions such as trimethylammonium, triethanolammonium,

or morpholinium. Obviously, sodium, potassium, and ammonium are preferred for reasons of economy and availability. The alkyl group of the N-(2-hydroxyalkyl)-N-methyltaurines may be either straight or branched chain and may be derived from either synthetic or natural sources. Typical compounds include, but are not limited to, N-(2-hydroxyalkyl)-N-methyltaurines of the above formula in which the radical R_1 is C_{10} , C_{12} , C_{14} , C_{16} , etc. as well as taurines in which R_1 is of the formula

n being from 11 to 17.

The surface active organic sulfate and sulfonate detergents which may be used in the present invention are the salts of the water-solubilizing cations mentioned above with organic sulfuric and sulfonic acids, the organic portion of which consists of the atoms C, H, O or amido nitrogen, and has from about 8 to about 20 carbon atoms. The hydrocarbon portion of the organic acid generally is characterized by at least one aliphatic or aryl-aliphatic radical containing between about 8 to 20 carbon atoms; however, the organic portion may also contain functional groups such as carboxyl, ether and the like. The aliphatic group may be saturated or unsaturated. Moreover, the aliphatic portion of the organic radical may be either a branched chain group derived from the older synthetic processes, such as polymerization of propylene, or it may be a straight chain group whereby the property of biodegradability can be obtained:

Typical classes of sulfates and sulfonates which may be used are:

(1) Alkanesulfonates of the formula

(2) Alkenesulfonates of the formula

(3) Sulfated alcohol-ethylene oxide condensates of the formula

(4) Alkoxyhydroxypropanesulfonates of the formula

(5) Taurates of the formula

(6) Sulfated fatty monoethanolamides of the formula

(7) Linear alkylbenzenesulfonates of the formula

wherein the phenylene group is randomly attached along the straight hydrocarbon chain.

(8) Alkyl phenoxy polyoxyethylene sulfates of the formula

(9) Amidomethanesulfonates of the formula

(10) Acyl isethionates of the formula

(11) N-(acyloxyethyl)sulfoacetamide of the formula

R in the foregoing eleven formulas represents an aliphatic hydrocarbon radical having about 8 to about 20 carbon atoms, but having about 8 to about 15 carbon atoms when it is attached to a phenylene group.

Some of the foregoing classes are illustrated by the following specific compounds:

sodium dodecyl sulfite

triethanolammonium dodecyl sulfate

sodium 3-dodecyloxy-2-hydroxypropane-1-sulfonate
the sodium salt of N-acyl isethionic acid, the acyl group

being derived from coconut fatty acids

the sodium salt of a sulfated condensate of 3 molar proportions of ethylene oxide and 1 molar proportion of stearyl alcohol

potassium dodecylbenzenesulfonate derived from phenyl-polypropylene

ammonium linear-alkylbenzenesulfonates having an average of 12 carbon atoms in the alkyl group

sodium paraffin sulfonate

To obtain the greatest synergistic effects, the N-methyltaurine salts of the present invention should be present in weight ratio of approximately 1:3 to 3:1 with respect to the sulfate or sulfonate detergent ingredient. It will be recognized that the essential synergistic activity obtained by the combination of the taurines of the present invention and sulfate or sulfonate detergents will be realized if these components are used in the appropriate ratios in a composition composed only of these two active ingredients, or in which the active ingredients are taken further in combination with one or more other components whereby a formulation, either liquid or solid, may be obtained for addition to an oil-in-water emulsion to be stabilized. For instance, in a typical formulation based upon the combination of a taurine as described above and a sulfate or sulfonate detergent, there may be from about 2% to about 35% of each of the taurine and the sulfate or sulfonate detergent components, up to 15% of an amide of a fatty acid in which one or both of the hydrogens of the amido nitrogen are replaced by lower alkyl or lower alkanol groups, and up to about 55% of an inorganic or organic builder to enhance the emulsifying activity of the combination of the present invention. In typical compositions employing emulsifiers in combination with other components, the total of the taurine and the sulfate or sulfonate will normally be between about 10% and about 40% by weight of the composition.

Typical amides which may be mentioned include, but are not limited to lauric monoethanol amide, lauric diethanol amide and lauric isopropanol amide. In other amides the lauric group may be replaced by myristoyl, palmitoyl, stearoyl, oleoyl, gadoloyl, erucoyl, etc., or mixtures of the foregoing, such as mixtures of lauroyl and myristoyl, and mixtures derived from naturally occurring fats and oils, such as coconut oil and tallow. In addition to the amides mentioned above, the unsubstituted amides, such as lauramide or the unsubstituted amide derived from coconut oil, may be used in granular products.

The inorganic builders contemplated are those commonly used in detergent formulations. Such builders include, but are not limited to, the alkali metal tripolyphosphates, tetraphosphates, hexametaphosphates, septaphosphates and decaphosphates, such as pentasodium tripolyphosphate. In addition certain orthophosphates and pyrophosphates such as potassium, sodium and ethanol, diethanol and triethanol pyrophosphates are useful. Other inorganic

compounds include alkali metal and ammonium silicates, carbonates, chlorides, sulfates and borates, and the alkaline salts of nitrilotriacetic acid. Examples are sodium silicate, bentonite, sodium carbonate monohydrate, sodium and potassium chloride, sodium and ammonium sulfate, sodium borate and the like.

Other adjuvants which may be used without altering the essential nature of this invention include, but are not limited to, the cellulosic anti-soil redeposition aids such as methylcellulose, hydroxymethyl cellulose, carboxymethyl cellulose, hydroxyethyl cellulose, carboxymethyl hydroxyethyl cellulose, and hydroxypropylcellulose. Certain organic polymers such as sodium polyacrylate and polyvinyl alcohol and the like have been found useful as builders in addition to some organic esters such as ethylene glycol monostearate and methyl palmitate. Higher fatty acid amides such as palmitylethanolamide, myristylethanolamide, laurylethanolamide, oleylethanolamide, myristamide, lauramide, stearamide, lauric diethanolamide, higher fatty acid amides of monoisopropanolamine (e.g. capryl, lauroyl and myristoyl isopropanolamide) and amide type mixtures prepared from mixtures of higher fatty acids derived from various fats, oils and waxes of animals, marine or vegetable origin may also be used as organic builders. Other amides suitable for use in our invention are N,N bis(lower alkylol) higher fatty acid amides such as N,N bis(2-hydroxyethyl) lauramide, N,N bis(2-hydroxyethyl) myristamide, N,N bis(2-hydroxyethyl) coconut fatty acid amide, N,N bis(2,3-dihydroxypropyl) lauramide, N,N bis(2,3-dihydroxypropyl) myristamide, N,N bis(3-hydroxypropyl) lauramide, N,N bis(3-hydroxypropyl) capramide, N,N bis(2-hydroxypropyl) lauramide, N,N bis(2-hydroxypropyl) myristamide, N,N bis(4-hydroxybutyl) lauramide and the like.

In the foregoing it will be obvious to those skilled in the art that of the alkali metal salts which may be used, sodium and potassium salts are the commercially most important.

In use, improved emulsification or emulsion stability is obtained by providing, in an emulsion of oil and water, for at least about 0.001% of a mixture of the taurine plus the sulfate or sulfonate detergent based on the weight of the water. For many applications, an amount of emulsifier between about 0.005% and 0.5% is particularly appropriate. However, it will be recognized that higher concentrations of emulsifier may be appropriate for systems which emulsify with greater difficulty.

For a further understanding of the present invention, reference may be had to the following examples. In the examples, the N-(2-hydroxyalkyl)-N-methyltaurines were obtained by reacting a 1,2-epoxyalkane with sodium N-methyltaurine in equimolar proportions. The 1,2-epoxyalkane was in turn obtained by epoxidizing a C₁₂-C₁₆ cut from a Ziegler type alpha-olefin.

The N-(2-hydroxyalkyl)-N-methyltaurines were obtained by reacting a C₁₂-C₁₃ primary alcohol with epichlorohydrin, and in turn epoxidizing the resultant intermediate to obtain a C₁₅-C₁₆ oxaalkyl epoxide. This last mentioned compound is then reacted in an analogous manner with N-methyltaurine.

To evaluate the emulsifying properties conveniently, a special test was devised as follows:

480 cc. of tap water at 116° F. were added to a 600 cc. beaker. 0.1 cc. of a 35% detergent solution or the equivalent was added to the water, followed by the addition of 20 cc. of Wesson oil. The mixture was then stirred for 1 minute at 435 r.p.m. with a Bodine motor (type NSE-11R) using a metal stirrer with a 5 x 1.6 cm. blade. The stirrer blade was placed so that 8 cm. of the shaft was immersed below the surface of the liquid. The emulsion was then allowed to stand at room temperature and the amount of oil separation was noted as a function of time.

Employing the foregoing test procedure, the emulsifying properties of a number of detergent solutions were measured.

5
EXAMPLE 1

The emulsifying property of a C_{12} - C_{16} N-(2-hydroxy-alkyl)-N-methyltaurine (HAMT) sodium lauryl sulfate (Na L.S.) and mixtures of the two were measured. The results are summarized in the following table: 5

¹ Prepared by sulfonating 1-hexadecene.² Alfol 1412 is a mixture of primary aliphatic alcohols about $\frac{2}{3}$ of which have 14 carbon atoms and about $\frac{1}{3}$ of which have 12 carbon atoms. "3EO" signifies that on the average, 3 oxyethylene units (or 3 moles of ethylene oxide) are combined with each mole of alcohol.

In most of the foregoing cases, as will be noted, either the N-(2-hydroxyalkyl)-N-methyltaurine or the other detergent used alone in a concentration of 0.056% was markedly less effective as an emulsifying agent, and in all cases the combination of detergents was more effective than would be predicted based on a linear addition of the individual components.

60

EXAMPLE 3

The test outlined in Example 1 was repeated again, this time using active ingredients in a concentration one-fifth of that employed in Example 1. In this illustration, the synergism between a C₁₂-C₁₆ HAMT and a potassium C₁₂-C₁₄ alcohol-3 ethylene oxide sulfate is illustrated. The results obtained are set forth in Table 12.

13

As already suggested, because of its superior ability as an emulsifier, the combination of an N-(2-hydroxyalkyl)-N-methyltaurine and a second detergent is of particular value in dishwashing formulations. The dishwashing detergent may be in either liquid or powder form; however, as is well known, the liquid form of detergent is by far the preferred form for consumer acceptance. In liquid form the formulation will consist essentially of from (A) 5% to 21% of a surface active organic compound which is a member of the group consisting of salts of water solubilizing cations with the organic sulfuric and sulfonic acids described above, (B) from 9% to 13% of the salt of C_{12} - C_{20} N-(2-hydroxyalkyl)-N-methyltaurine with a water solubilizing cation, the ratio of (A) to (B) being between 3:1 and 1:3, and (C) sufficient water to yield a liquid.

A typical formulation embodying the present invention adapted to be used as a liquid dishwashing detergent may have the following composition:

	Percent
Alkali metal or ammonium alcohol-3.1 ethylene oxide sulfate ¹	8-15
Alkali metal or ammonium alkyl (C_{12} - C_{14}) sulfate	3-6
C_{14} - C_{16} HAMT ²	9-13
Solubilizers	2-15
Salts ³	0-4
Opacifier	0-1
Perfume, colorant, etc.	0-0.2
Water, balance to make 100%.	

¹ Condensates containing from 1 to 10 moles of ethylene oxide per mole of alcohol may be used. The alcohol contemplated is the hydroxy derivative of an acyclic, aliphatic hydrocarbon which contains from about 12 to about 14 carbon atoms.

² The N-(2-hydroxyalkyl)-N-methyltaurines may be pure components; however mixtures in the range of C_{14} and C_{16} alkyl groups will be of greater practical availability. The cation may be an alkali metal or ammonium. Oxa-HAMT may be substituted for HAMT in the same amount.

³ Salts are frequently desired to increase the viscosity of the liquid for purposes of consumer acceptance. Sodium and potassium chlorides, sulfates, monethanol ammonium sulfates, and bicarbonates are particularly useful in this respect.

With respect to the solubilizers mentioned in the foregoing formulation, all materials commonly classified as solubilizers would be suitable. Included are the various alcohols, preferably the saturated, aliphatic type, which also provide freeze-thaw stability to the detergent. These alcohols may be mono- or polyhydric and may contain inert solubilizing groups such as ether linkages. Examples of monohydric alcohols are methyl, ethyl, n-propyl, isopropyl and n-butyl alcohol or mixtures thereof. Higher monohydric alcohols are not preferred since they have a comparatively undesirable odor and generally exhibit less solubility in water. Among the many suitable polyhydric alcohols are ethylene, propylene, and hexylene glycol, glycerol or mixtures thereof. Suitable alcohols possessing ether linkages are the monoethyl ethers of ethylene and diethylene glycol, the monobutyl and monomethyl ethers of diethylene glycol, dioxane and the like.

In lieu of the foregoing alcohols, the low molecular weight aryl and alkylarylsulfonates may also be used as solubilizers, such as the alkali metal alkylarenesulfonates derived from benzene, naphthalene, diphenyl and diphenylmethane. In addition, the soluble alkali metal and ammonium sulfonates of benzene, toluene, cumene and xylene may also be used. Examples are the ethanol, diethanol and triethanol ammonium benzene sulfonates and potassium and sodium toluene sulfonate.

EXAMPLE 4

The detergent actives mentioned in the above formula were tested for dishwashing performance by comparison against a standard commercial liquid dishwashing detergent. Batches of plates soiled under standard conditions were washed in dishwashing solutions prepared by adding 6 grams to 6 quarts of water at 120° F. of either

14

the standard dishwashing detergent or a test formulation. The number of plates washed before disappearance of the suds was observed, with the following results:

A comparison was made between test detergent (A) containing 12% of a C_{12} - C_{16} N-(2-hydroxyalkyl)-N-methyltaurine and 15% of lauryl alcohol sulfate, test detergent (B) containing 27% of lauryl alcohol sulfate, test detergent (C) containing 27% of N-(2-hydroxyalkyl)-N-methyltaurine, and test detergent (D) which was a commercial liquid dishwashing detergent. Test detergent (A) washed 41 plates, test detergent (B) washed 9 plates, test detergent (C) washed 33 plates, and the commercial dishwashing detergent (D) washed 38 plates. These data clearly show a substantial improvement accruing from the use of a mixture of N-(2-hydroxyalkyl)-N-methyltaurine and a sulfate or sulfonate in dishwashing tests. In all of the test detergents, the sodium salts were used.

EXAMPLE 5

An illustrative commercial dishwashing formulation employing the present invention is as follows:

Sodium Alfol 1412 sulfate ¹	3.0
Sodium Alfol 1412-3.1 ethylene oxide sulfate ²	11.0
C_{15} - C_{16} HAMT	10.0
Opacifier	0.4
Perfume	0.15
Hexylene glycol	3.5
NaCl	2.5

Water, balance to make 100%.

¹ A C_{12} - C_{14} straight chain alcohol sulfate.

² The sulfonated condensate of Alfol 1412 with 3 moles of ethylene oxide.

EXAMPLE 6

The synergistic properties of the combination of the present invention is further illustrated by tests summarized in the following table.

	Formulation tested	Commer-				
		A	B	C	D	wash-
						ing
						liquid
45	NH_4 Alfol 1412-3.1 E.O. sulfate ¹	14.1	14.1	14.1	14.1	
	Sodium C_{14} HAMT	5.7				
	Sodium C_{16} HAMT		5.7			
	Sodium C_{18} HAMT			5.7		
	Ethyl alcohol	13.6	13.6	13.6	13.6	
	Water and misc.	66.6	66.6	66.6	72.3	
50	Number of plates washed	43	49	28	19	39

¹ The sulfated condensate of a C_{12} - C_{14} linear alcohol with 3.1 moles of ethylene oxide.

The foregoing shows that excellent liquid detergents can be formed by combining HAMT with a sulfate or sulfonate detergent.

The mildness of detergents towards hands is of particular commercial importance in the manufacture and sale of dishwashing products. We have found that the combination of sulfate or sulfonated detergents with methyltaurine salts according to the proportions of the present invention results in a composition of unexpected mildness. In three epilated guinea pig (E.G.P.) tests, the results of which are provided in Table 13, the mildness of several sodium Alfol sulfate (C_{12} - C_{14} straight chain alcohol sulfate) solutions was determined by applying specified amounts of the active material to the exposed skin of the animals being tested. Two such applications of the active material were made to ten separate portions of skin and the treated portions were observed on two occasions, twenty-four hours after each application. The average erythema reading in the tests of Table 13 is based solely upon the observations after the second application. The number (index of irritation) in the "Average Erythema Reading" column indicates the extent of the red-

- (c) from about 0% to about 55% of an alkaline phosphate builder; and
 (d) from about 0% to about 15% of an organic amide of a fatty acid having from 12 to 22 carbon atoms in which at least one of the hydrogens of the amide nitrogen is replaced by a member selected from the group of lower alkyl and lower alkanol groups.

4. A liquid detergent concentrate consisting essentially of

- (a) from 9% to about 13% of a taurine selected from the group of compounds having the formula

wherein R_1 is an alkyl group having from 12 to 18 carbon atoms or an oxaalkyl radical having the formula

- n being 11 to 17, and M is a water-solubilizing cation; (b) from about 5% to about 21% of a salt of a water-solubilizing cation with an organic surface active organic detergent selected from the group consisting of sodium dodecyl sulfate, alkanesulfonates of the formula

alkenesulfonates of the formula

sulfated alcohol-ethylene oxide condensates of the formula

in which x is 1-10, alkoxyhydroxypropanesulfonates of the formula

taurates of the formula

sulfated fatty monoethanolamides of the formula

and linear alkylbenzene sulfonates of the formula

wherein the phenylene group is randomly attached along the straight hydrocarbon chain, alkyl phenoxy polyethylene sulfates of the formula

in which X is 1-10, wherein, in the foregoing formulas, R is an aliphatic hydrocarbon radical having about 8 to about 20 carbon atoms and, when attached to a phethylene group, R is an aliphatic hydrocarbon radical having about 8 to 15 carbon atoms and M is a water-solubilizing cation; and

- (c) sufficient water to yield a liquid concentrate having a pH of at least about 8, said taurine and said detergent being present in a weight ratio between about 3:1 and 1:3.

5. A liquid detergent concentrate according to claim 4 consisting essentially of:

- (a) from 3% to 6% of an alkyl sulfate having from 12 to 14 carbon atoms in the alkyl group with a cation selected from the group consisting of the alkali metals and ammonium;

(b) from 8% to 15% of the salt of the sulfate of the condensate of an alcohol of an acyclic aliphatic hydrocarbon with from 1 to 10 moles of ethylene oxide, there being from 12 to 14 carbon atoms in the hydrocarbon group, with a cation selected from the group consisting of the alkali metals and ammonium;

- (c) from 9% to 13% of said taurine, wherein said taurine has from 12 to 14 carbon atoms in R_1 , and M is selected from the group consisting of the alkali metals and ammonium,

(d) from 2% to 15% of a solubilizing agent selected from the group consisting of lower monohydric alkanols, lower alkylene and polyalkylene glycols, lower alkyl ethers of lower alkylene glycols, glycerol and dioxane and low molecular weight alkali metal and ammonium aryl and lower alkylaryl sulfonates; and

- (e) sufficient water to yield a liquid concentrate.
